UNITED STATES PATENT OFFICE.

SAMUEL BARUCH, OF NEW YORK, N. Y.

COOLER FOR INTERNAL-COMBUSTION-ENGINE RADIATORS.

1,823,812.

Specification of Letters Patent.

Patented Dec. 2, 1919.

Application filed May 25, 1918. Serial No. 236,611.

To all whom it may concern:

Be it known that I, SAMUEL BARUCH, a citizen of the United States, and a resident of New York city, borough of Manhattan, in the county of New York and State of New York, have invented a new and Improved Cooler for Internal-Combustion-Engine Radiators, of which the following is a full, clear, and exact description.

10 My invention has for its object to provide a cheap and efficient cooler for internal combustion engine radiators, with which is combined a water level indicator for the radiator.

15 Additional objects of the invention will appear in the following specification in which the preferred form of my invention is described.

20 In the drawings similar reference characters refer to similar parts in all the views, in which—

25 Figure 1 is a sectional fragmentary view illustrating the construction of my invention and the manner in which it is secured to a radiator, and

Fig. 2 is a perspective of the bracket having the bearing through which is disposed the spindle of the water level indicator.

30 By referring to the drawings, it will be seen that the radiator 5 is of the usual construction with a cap 6 in which there is made an opening 7. The depending neck 8 on a drum 9 has a shoulder 10 which rests against the top of the cap 6, the terminal 11 of the 35 depending neck 8 which is of less diameter than the body of the neck being disposed through the opening 7, and having an outer thread 12. Disposed against the bottom of the cap 6, there is a bracket 13 having an 40 opening 14 through which the terminal 11 of the depending neck 8 is disposed, a washer 15 being disposed against the bracket 13. A nut 16 is employed which meshes with the 45 thread 12 on the terminal 11 of the neck which serves to hold the drum 9 and the bracket 13 in position.

46 The neck 8 depends from around an opening 17 in the head 18, the head 18 having a seat 19 at the said opening. Disposed in the 50 drum 9, there is a perforated tube 20, the lower end 21 of which is seated in the seat 19. The upper end 22 of the perforated tube 20 is seated in a seat 23 in a head 24 which is 55 removably secured to the top of the drum 9 by means of threads 25.

It will be understood by referring to the

drawings that steam from the radiator will pass up the tube 20 into the drum 9 where it will be condensed because of the cooling effect of the air against the drum 9 as the 60 automobile on which the radiator 5 is mounted is driven along the ground. It will also be understood that this cooling effect will be increased because of the air which will flow up the radiator overflow pipe 26 to and through the tube 8. The vapor and the air from the radiator overflow pipe 26 will pass out through the perforations in the tube 20 to the drum 9. When the vapor is condensed the fluid will flow through the lower perforations in the tube 20 back to the radiator 5. In the cap 24 there are openings 27 to permit the escape of any steam.

65 In the cap 24 there is an opening 28 through which is disposed a spindle 29, the 70 said spindle extending down through the neck 8 and through a bearing 30 in the bracket 13. At the lower end of this spindle 29 there is secured a float 31 which is disposed in the water in the radiator as shown 75 in Fig. 1 of the drawings, this float 31 serving to hold the spindle 29 upwardly with its stop 32 abutting against the bracket 13 at the bearing 30. However, when the water in the radiator 5 is below a predetermined 80 level, the spindle 29 will move downwardly so that the ball 33 at the top of the spindle, which is disposed beyond the cap 24, will rest against the said cap and indicate to the 85 driver of the car that the radiator should be 90 refilled.

Having thus described my invention, I claim as new and desire to secure by Letters Patent:

1. In a cooler for internal combustion engine radiators, a drum with a thread at its sides and adjacent its top and a head at its bottom provided with an opening, a tube disposed in the drum spaced from the sides of the latter and having its bottom disposed 100 in the opening, the tube having perforations spaced above each other in the drum, and a cap with openings for its sides, and a seat in which the upper end of the tube is disposed, the cap being provided with a thread 105 normally meshing with the thread on the drum.

2. In a cooler for internal combustion engine radiators, a drum having a head at its top and another head at its bottom with an 110 opening, a neck depending from the last mentioned head from around the opening,

the neck being spaced from the sides of the drum at the last mentioned head and having means at its bottom by which it may be secured to a radiator cap for supporting the drum spaced above the radiator cap, and a perforated tube extending upwardly in the drum from the opening in the head at the bottom of the drum.

3. In combination with a radiator cap having an opening therethrough, a drum disposed above the cap and having heads at its top and bottom, there being an opening in the head at the bottom of the drum, a neck depending from the bottom head around its opening and spaced from the sides of the drum, the neck extending through the open-

ing in the radiator cap, a bearing member disposed below the cap and having an opening through which the neck extends, means to hold the neck, the radiator cap and the bearing member in position relatively to each other, a perforated tube disposed in the drum and extending to the opening, there being an orifice in the head at the top of the drum, a spindle disposed through the bearing in the bearing member, in the perforated tube and through the orifice in the head at the top of the drum, and a float at the lower end of the spindle, there being an opening in the upper head of the drum beyond the side of the tube.

SAMUEL BARUCH.
